UNITED STATES PATENT OFFICE.

CASS L. KENNICOTT, OF CHICAGO HEIGHTS, ILLINOIS, ASSIGNOR TO THE KENNICOTT COMPANY, OF CHICAGO, ILLINOIS, A CORPORATION OF ILLINOIS.

CHEMICAL-PUMP CONTROLLER FOR WATER-SOFTENING APPARATUS.

1,176,368.

Specification of Letters Patent. Patented Mar. 21, 1916.

Application filed December 9, 1915. Serial No. 66,010.

To all whom it may concern:

Be it known that I, CASS L. KENNICOTT, a citizen of the United States, residing at Chicago Heights, in the county of Cook 5 and State of Illinois, have invented a new and useful Improvement in Chemical-Pump Controllers for Water-Softening Apparatus, of which the following is a specification.

10 My invention relates to water-softening apparatus of the type in which the chemicals to be used in softening the water under treatment are held in a container mounted below the normal water level in the treating reservoir, and in which a pump is employed for lifting the fluid chemicals or chemical solution from the container to the treating reservoir.

More particularly, the invention relates 20 to that type of water-softening apparatus in which chemicals flow to the pump from a chemical sump which, in turn, receives the chemicals from a regulating tank, or other controlled supply, which may at times 25 supply liquid to the sump less rapidly than it is removed by the pump.

It is the object of my invention to provide 30 a means by which, under the above-named conditions of operation, the pump may be prevented from emptying the sump, and 35 which will accomplish this result without interfering with the continuous operation of the pump, or supplying liquid to the sump from any source other than the chemical-supply means.

The foregoing objects are accomplished 40 by the construction and combination of parts illustrated in the accompanying drawings and described in the specification annexed hereto.

In the drawings, Figure 1 is a front elevation, partly in section and partly diagrammatic, of a water-treating plant embodying my invention; Fig. 2 is a view of 45 the lower portion of the apparatus shown in Fig. 1, the pump of Fig. 2 being a centrifugal pump having another means for controlling its operation; Fig. 3 is a similar view of a still further modification of the 50 apparatus, and Fig. 4 is an enlarged vertical section showing a form of balanced valve adaptable for use with my pump controller.

Referring more particularly to the draw-

ing, the numeral 10 designates the main treating reservoir of my apparatus, above 55 which is mounted a dividing box 11 to which the raw water is supplied as by a pipe 12 controlled by a float valve 13, the float of which rides upon the surface of the liquid in the dividing box. In the box 11 the 60 raw water is divided into two streams, a large stream which passes outwardly through the pipe 14 and a relatively small stream which flows through the pipe 15 to the chemical regulating means, as will later 65 appear. Directly beneath the outlet of the pipe 14, there is a mixing-plate 16 upon which the raw water impinges to be there mixed with the inflowing chemicals as will later appear. Below the mixing-plate 16 70 the water passes downwardly through a flaring conduit 17, known as a downtime, in which it is designed that the raw water and chemicals shall thoroughly intermingle and react to cause a precipitation of the objectionable materials of the water. A conical bottom 18, below the downtime 17, serves to collect this precipitate and to permit it to be drawn off from time to time, as by a 75 sludge pipe 19 which empties into a sludge sump 20. The treated water rises through the annular space surrounding the downtime conduit 17 and after passing through a filter-bed 21 may be drawn off as by the outlet 22.

It is the function of the relatively-small 80 pipe 15 leading from the dividing box 11 to actuate a means by which the flow of chemicals is accurately regulated in proportion to the flow of raw water. This is accomplished by a regulating tank 23 into 85 which the pipe 15 discharges and within which there is mounted a progressively-rising float 24 which is connected by a cable 25 to a lift-pipe 26 pivoted for movement in a vertical plane within the chemical tank 27. The chemicals entering the upper end of the lift-pipe pass therethrough and are discharged by a spout 28 connected with the lift-pipe into a chemical sump 29. From 90 the bottom of this sump the regulated chemicals are withdrawn as by a pump 30 which is preferably constantly driven, as will later appear, and are discharged from the pump 95 through a pipe 31 onto the top of the mixing-plate 16, there mixing with the entering 100 105

raw water which is discharged from the outlet 14.

It will readily be observed that if the flow of raw water should be cut off or reduced below a certain definite point, the regulating float 24 would maintain this pipe 26 stationary, or lower it so slowly that the constantly-operating pump 30 would empty the chemical sump 29 and begin to pump air. To prevent this condition of affairs from occurring, there is provided a by-pass pipe 32 connected to the discharge line 31 of the pump 30 and having its outlet end adapted to discharge into the sump 29. Within this outlet end there is mounted a balanced valve 33 which, as shown in Fig. 4, may be of the simple butterfly or pivoted damper type, this valve being controlled by a float 34 which rides upon the surface of the liquid within the sump. When, therefore, the pump 30 tends to withdraw the chemical from the sump faster than it is supplied by the regulating means, the falling liquid level within the sump operates through the float 34 to open the by-pass valve 33, whereby the pump acts merely to circulate the liquid from the sump and back to the same again. The pump 30 may, therefore, be operated constantly and at a speed sufficient to take care of the maximum chemical feed, and will nevertheless be kept constantly primed when the chemical feed is small or has ceased altogether.

For constantly driving the pump 30, I have shown a crank-shaft 35, which is the same shaft utilized for operating the chemical stirrer 36 and is driven by an electric motor 37. If desired, a pipe 38 leading from some source of water-supply, either softened or unsoftened, may be arranged to discharge into the sump 29 for washing out the same or for diluting the chemicals therein in either constantly or intermittently as may be desired.

In Fig. 2 I have shown a modified arrangement of the parts in which the pump, designated 40, is of the centrifugal type, being driven by miter gears from the shaft 35, as by a shaft 41. In this form of the invention the float 34 is carried by an angular arm 42 which operates a valve 43 directly in the outlet pipe 44 of the centrifugal pump. It is, of course, well understood that in this form of pump the outlet may be closed without injury to the apparatus, the only result being that the water within the pump is churned and may tend to become slightly heated in time. In the apparatus shown in Fig. 2 it will be seen without further explanation that when the level of chemicals within the sump falls, the float 34 will drop and by cutting off the outlet from the pump will prevent further emptying of the sump.

In Fig. 3 a chemical sump 45 somewhat

larger than the sump 29 is shown, and a centrifugal pump designated 46 is mounted directly within the sump, the outlet pipe 47 being controlled by a float 48, as before noted in connection with Fig. 2. A valved water-supply pipe 50 similar in function to the pipe 38 is shown in Fig. 3 in position to discharge into the chemical sump. 70

While I have shown and described in considerable detail some specific embodiments of my invention, it is to be understood that this showing and description is illustrative only and for the purpose of making my invention more clear and that I do not regard the invention as limited to these details, nor any of them, except in so far as I have included such limitations within the terms of the following claims, in which it is my intention to claim all novelty inherent in my invention as broadly as is possible in view 80 of the prior art. 85

What I claim as new and desire to secure by Letters Patent is:

1. In a water-softening apparatus and in combination, a raw-water supply-means, a chemical sump, means for feeding chemicals to the sump in varying amounts, a continuously-operating pump for withdrawing chemicals from the sump and supplying them to the raw water, and a valve operable 95 by change of level of the chemical in the sump for controlling the supply of chemical pumped to the raw water. 90

2. In a water-softening apparatus and in combination, a raw-water supply-means, a chemical sump, means for feeding chemicals to the sump in regulated amounts, a continuously-operating pump for withdrawing chemicals from the sump and supplying them to the raw water, and a valve located on the 105 discharge side of the said pump and operable by change of level of the chemical in the sump for controlling the supply of chemicals pumped to the raw water. 100

3. In a water-softening apparatus and in combination, a raw-water supply-means, a chemical sump, means for feeding chemicals to the sump in proportion to the supply of raw water, a continuously-operating pump for withdrawing chemical from the sump 115 and supplying it to the raw water, a by-pass conduit extending from the discharge side of the said pump to the said sump, a valve for controlling the said conduit, and means for operating the said valve by change of 120 level of the chemical in the sump. 110

4. In a water-softening apparatus and in combination, a treating reservoir, a raw-water supply-means entering the upper portion of the said reservoir, a chemical sump 125 located below the said raw-water supply-means, means for feeding chemicals to the sump in proportion to the feed of raw water, a continuously-operating pump for withdrawing chemical from the sump and sup- 130

plying it to the upper portion of the said treating reservoir, a by-pass conduit communicating with the discharge side of the pump and opening into the said sump, a
5 valve for controlling the said by-pass, and a float riding upon the surface of the liquid within the said sump and having operative

connections with the said valve to open the latter as the liquid level within the sump falls.

CASS L. KENNICOTT.
